FLASH LIGHT CAP

Otto C. Britsch, New York, N. Y., assignor to
Henry Hyman, Brooklyn, N. Y.

Application February 14, 1931. Serial No. 515,665

4 Claims. (Cl. 240—10.65)

The invention is a flashlight cap which snaps open and closed and is formed with only three parts so that it is materially simplified as compared with other similar caps.

5 The object of the invention is to simplify the construction of flashlight caps.

Another object of the invention is to provide a flashlight cap which is so constructed that the insulation between the parts thereof is eliminated

10 so that the base plate may be made of metal.

A further object of the invention is to provide a flashlight cap in which the spring that snaps the cover in both the open and closed position also forms the contact with the battery.

15 And a still further object of the invention is to provide a flashlight cap which is of a simple and economical construction and which is readily assembled.

With these ends in view the invention embodies a base plate, a cover, and a spring for holding the cover in the base plate.

Other features and advantages of the invention will appear from the following description taken in connection with the drawing, wherein:—

20 Figure 1 is a view showing an elevation of the flashlight with the cover in the open position.

Figure 2 is a cross section through the upper end of the flashlight also showing the cover in the open position.

25 Figure 3 is a plan view showing the base plate with the flashlight casing omitted and the cover broken away.

Figure 4 is a view similar to that shown in Figure 2 with the cover in the closed position.

30 Figure 5 is a detail showing the base plate.

Figure 6 is a detail showing the cover.

Figure 7 is a detail showing the spring.

In the drawing the device is shown as it would be made wherein numeral 1 indicates the base plate, numeral 2 the cover, and numeral 3 the spring.

35 The base plate 1 may be made of any suitable material or of any desired size, or arranged in any suitable manner. In the design shown it is made with a lamp opening 4 adjacent one end and a threaded sleeve 5 extending downward from the under side thereof in which a lamp as indicated by the numeral 6 may be held. At the opposite end of the base is a slot 7 and a rectangular shaped opening 8 with a raised web 9 between them, and in the side of the base is a notch 10 which is placed over a seam in the side of the flashlight casing. A leg 11 extends downward from the end of the base to form a spacer to locate the base plate a predetermined

distance from the end of the battery in the casing, and so that there is no direct contact between the two.

The cover 2 as shown in Figure 6 is formed in a somewhat semi-circular shape with a small projection 12 at the forward end by which it may be raised and an extension 13 at the opposite end which extends through the slot 7 and under the web 9 as shown in Figures 2 and 4. This extension is formed with an indented rib 14 to add strength thereto and the lower end is provided with a notch 15 in which an extension 16 at one end of the spring is held and it will be noted that a similar extension 17 at the opposite end of the spring is located in the end of the opening 8 of the base. The spring 3 is a flat piece of material formed in the shape of a U and has a projection 18 extending downward from one side which will engage the side of a cell 19 when the cover 2 is open as shown in Figure 2 to complete a circuit from the cell 19 through the spring 3, the base plate 1 and the lamp 6 to the other cell 20. It will be understood that the opposite ends of the two cells are connected.

40 It will be understood that changes may be made in the construction without departing from the spirit of the invention. One of which changes may be in the use of the cap with any other type of flashlight and with the design or arrangement of the base changed to accommodate the casing thereof. Another change may be in the design or arrangement of the spring or of the contact point extending therefrom, and still another may be in the arrangement of the cover extension in relation to the spring and base as this may be changed for different designs.

45 The construction will be readily understood from the foregoing description. In use the cap may be assembled by inserting the extension 13 of the cover through the slot 7 and under lugs 21 which may be provided at the ends of the slot, and then one end of the spring is placed in the notch 15 at the end of the extension 13 and the other snapped in the opening 8 as shown in Figure 2. The entire cap is then assembled and ready to be assembled or installed in the flashlight casing.

50 It will be noted that this entire cap is formed with three parts as shown in Figures 5, 6, and 7, and each of these parts is very simple, whereas all similar caps require many parts and the parts are very complicated in construction and also in assembling.

55 Having thus fully described the invention what I claim as new and desire to secure by Letters Patent, is:—

1. In a flashlight cap of the type having a cover that snaps open and closed, a cover with a member extending downwardly and inwardly at one end, a base plate having an opening therein in which said downwardly extending member of the cover slides, and a spring installed in an opening in said base plate with an end thereof engaging the end of said downwardly extending member of the cover and positioned to hold said cover in either the open or closed position.

2. In a flashlight, a base provided with openings therein, a cover with an extension at one end thereof extending through an opening in said base and slideable in said opening, and a U-shaped spring having one side bearing against the edge of an opening in the base and the other against said extension of the cover, said cover extension and spring being shaped and arranged so that the spring snaps and holds the cover open and also snaps and holds the cover closed.

3. In a flashlight cap, a base with openings therein, a cover having an extension at one end, a spring with a contact point extending there-

from, means for holding a lamp in said base, a downwardly extending spacing member at one end of the base for locating the same, means for fulcruming said cover in said base with the extension engaging one end of the spring the other end of which is positioned in the base, said spring arranged to hold said extension below said fulcrum with the cover closed and above said fulcrum with the cover open, and a member on said base for limiting the upward movement of said cover.

4. In a flashlight cap of the type where the cover snaps to both the open and closed positions, a base, a battery, a lamp held in the said base with one terminal thereof engaging one terminal of the battery, a cover fulcrumed in said base, a spring positioned to snap said cover in both the open and closed positions, and a projection on said spring adapted to engage the opposite terminal of said battery when the cover is open to complete a circuit through said base and lamp.

OTTO C. BRITSCH.
